US00D509200S

(12) **United States Design Patent** (10) Patent No.: **US D509,200 S**
Harris (45) Date of Patent: **** Sep. 6, 2005**

(54) **SINGLE UNIT COMFORTABLE WIRELESS COMMUNICATION DEVICE**

(75) Inventor: **Arlene Joy Harris, Del Mar, CA (US)**

(73) Assignee: **Dyna LLC, Del Mar, CA (US)**

(**) Term: **14 Years**

(21) Appl. No.: **29/205,217**

(22) Filed: **May 10, 2004**

(51) **LOC (8) Cl. 14-03**

(52) **U.S. Cl. D14/138**

(58) **Field of Search** D14/137, 138, D14/147-148, 247-248, 144, 143, 341-347, 205, 206, 223; 379/433.01-433.13, 434, 430; 455/550.1-90.3, 575.3, 566, 575.1, 575.4, 575.6, 556.1, 556.2; D21/517; 345/169

(57) **CLAIM**

The ornamental design for a single unit comfortable wireless communication device, as shown and described.

DESCRIPTION

FIG. 1 is a perspective view of a design for a single unit comfortable wireless communication device in accordance with a first embodiment;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a perspective view of a design for a single unit comfortable wireless communication device in accordance with a second embodiment;

FIG. 9 is a top plan view thereof;

FIG. 10 is a bottom plan view thereof;

FIG. 11 is a right side elevational view thereof;

FIG. 12 is a left side elevational view thereof;

FIG. 13 is a front elevational view thereof; and,

FIG. 14 is a rear elevational view thereof.
